HOT AIR CIRCULATING ATTACHMENT FOR
HEATERS

Carl E. Bazley, Auburn, N. Y.

Application June 27, 1940, Serial No. 342,770

1 Claim. (Cl. 126—105)

This invention relates to heating apparatus and particularly to means for distributing the air of a hot air heater or furnace among the hot air pipes leading from the heating chamber of the casing of the furnace, which means may be applied, as a unit, to the furnace, or the heated air chamber thereof, by merely cutting a hole in the top wall of the chamber centrally thereof and placing the unit on the top of the chamber with the fan of the unit depending through the hole 10 into the chamber.

It further has for its object means, as a baffle plate or deflector, which may be readily installed, when desired, in position to direct a required amount of heated air to a certain hot air pipe, which otherwise does not receive a sufficient amount of air or sufficient pressure to move the air through that hot air pipe, or to prevent undue gyroscopic action of the air, which baffle means is applied to the chamber through the central opening and is supported from the margin of the wall around the central opening.

It further has for its object a construction by which a circulating unit may be applied to the top wall of the heating chamber without being secured thereto but on the contrary so mounted as to be balanced on the margins of the wall around the central opening.

The invention consists in the novel features and in the combinations and constructions hereinafter set forth and claimed.

In describing this invention, reference is had to the accompanying drawing in which like characters designate corresponding parts in all the views.

Figure 1 is a fragmentary view of a hot air heater or furnace provided with this invention.

Figure 2 is an elevation of the circulating unit looking to the right in Figure 1.

Figure 3 is a plan view of the frame and the distributing unit.

Figure 4 is a fragmentary plan view of the furnace, the air circulating unit being removed.

1 designates a heater; 2 the outer casing, and 3 the hot air chamber of the casing, from which extends the hot air pipes 4 leading to the rooms to be heated. The furnace and the casing may be of any well known construction.

5 designates the circulating or distributing unit, which is applied to the chamber 3, as a unit, and preferably without the use of fastening means. This unit consists of a suitable frame including a base 6 and a bracket 7 extending upwardly from one edge of the base, an electric motor 8 supported from the bracket, with its

shaft 9 vertical, a centrifugal fan 10 below the base, and a shaft 11 connecting the fan 10 to the shaft 9, as through any suitable coupling, at 12, the shaft 11 extending centrally through and having a bearing in the base 6. The centrifugal fan is arranged with its inlet presented downwardly, and is of considerably less diameter than the heater 1, so that the air is drawn upwardly through the casing of the heater 1 and the heated air drawn into the center of the fan and thrown centrifugally outwardly with sufficient pressure to distribute it among the pipes 4 and keep it moving in the pipes 4. Hence, the cold air does not mix with the warm air being thrown by the fan through the pipes 4.

The unit is so mounted on the top wall 13 of the chamber 3, that it is balanced, and no means is required to secure it to the top wall 13. The top wall 13 is provided with a central opening 14 of comparatively small diameter but of sufficient diameter to permit the centrifugal fan 10 to be inserted therethrough, and the base 6 is supported from the margin of the top wall around the opening 14. It is here shown as so supported by a plate 15, usually of an asbestos material, sufficiently large to rest on the margin of the wall around the opening 14, as seen in Figure 1. Preferably a pad 16 of resilient material as sponge rubber is interposed between the base 6 and the plate 15. The plate 15 and the pad 16 are formed with central openings for the shaft 11 and are applied to the shaft 11 before the shaft 11 is coupled to the motor shaft 9 or before the fan is secured to the shaft 11, although they may be applied to the shaft 11 in any other manner.

For facilitating the balancing, the base is provided with converging side edges 18 which converge toward the edge of the base remote from the bracket 7, so that the base has something analogous to a three-point mounting. Thus, the unit may be applied to the top wall of the casing 13 by cutting the hole 14 and then manipulating the unit with the plate 15 and pad 16 thereon in such a manner that the fan 10 passes through the opening 14 and the plate 15 rests on the margins of the wall around the opening 14.

Oftentimes, because of the length and the angle of one or more hot air pipes, special means is provided for distributing the air to such pipes, and also in some instances, it is desirable to prevent a gyroscopic action of the air being thrown by the fan 10. In order to distribute the air to such pipe or pipes that do not otherwise receive its proper share, or break up the gyroscopic action, a baffle 19 may be provided

located to direct more air into a certain pipe or located merely to break up the gyroscopic action. The feature of this baffle is that it is also applied to the furnace or the air chamber 3 through the opening 14 and supported from the margin of the wall around said opening.

As here shown, the baffle 19 is provided with a flat hook or bill 20 at the inner end thereof which provides a slot at 21, and in applying the baffle to the top wall 13 of the chamber 3, the baffle is inserted through the opening 14 and the baffle manipulated, so that the margin of the wall around the opening passes into the slot 21 with the bill or hook 20 overlying the upper side of the margins, where it may be secured in position in any suitable manner, as by a set screw 22. By this arrangement the baffle can be located in any radial angle or any radial position.

By this unit and the use of a fan of small diameter located as set forth, a small motor extremely economical in the use of electric power may be used and the warm air distributed evenly to better advantage with a circulating fan of the vane type.

The motor is controlled by any suitable thermostatic means not forming part of this invention, but briefly, the thermostatic element is controlled by the temperature of the heated air being discharged from the chamber 3 into the pipes 4, and when a predetermined high temperature of the air is reached, the thermostatic control closes a circuit through the motor and causes the motor to run and when the temperature

falls below this predetermined high point, the motor stops. For instance, assume that the temperature desired in the rooms of a dwelling is 68° F., the thermostat may be set for a temperature of approximately 125° in the chamber 3, and when the temperature in the chamber 3 reaches 125°, the motor 8 will be energized and when it drops below that temperature, the motor will stop. The control of the drafts either by a thermostat or by hand may be controlled in any suitable manner.

What I claim is:

The combination with a heater having the usual outer casing surrounding it and formed with the usual hot air chamber at the top thereof of above the heater from the peripheral wall of which chamber the hot air pipes lead; of the top wall of said chamber being formed with a central opening, and means for distributing the air among said pipes comprising a unit including a frame, an electric motor carried by the frame and arranged with its shaft vertical, a fan located in the chamber and placeable therein through said opening, a shaft connecting the fan and the motor shaft, said frame being carried by the margins of the wall around said opening and the unit being arranged to balance in vertical position, a baffle plate insertable into the chamber through said opening and having means for supporting it from the margin of the wall around said opening in position to extend substantially radially of the chamber.
